UNITED STATES PATENT OFFICE.

WILLIAM HUMANS, OF CAMBRIDGEPORT, ASSIGNOR, BY MESNE ASSIGNMENTS, OF ONE-HALF TO JOHN H. COLLAMORE, OF BOSTON, MASS.

ELECTRIC ANNUNCIATOR AND COMMUNICATING APPARATUS.

SPECIFICATION forming part of Letters Patent No. 277,286, dated May 8, 1883.

Application filed June 9, 1880. (No model.)

To all whom it may concern:

Be it known that I, WILLIAM HUMANS, of Cambridgeport, county of Middlesex, State of Massachusetts, have invented an Improvement in Electric Annunciators and Communicating Apparatus, of which the following description, in connection with the accompanying drawings, is a specification.

My invention relates to electric annunciators and communicating apparatus, and is shown embodied in a hotel-annunciator and apparatus connected therewith.

In the signaling apparatus now commonly used for hotels and similar purposes an annunciator is used to enable a room occupant to signal to an attendant at the hotel-office that something is wanted, the annunciator-drop indicating from what room the signal comes, after which the want may be made known by communicating through speaking-tubes, or an attendant is at once sent to the said room.

The invention consists in the arrangement of the circuits and methods of connecting them, as will be hereinafter more fully described. In the arrangement of the circuits herein shown each of the rooms is in a branch, normally open, of a battery-circuit, the said branch passing through the coils of a telephone in the corresponding room, and those of an electro-magnet controlling an annunciator-drop at the annunciator of the hotel-office, and all the said branches uniting and passing through a single signal-bell. The circuit from all the branches thus united is controlled by a switch or circuit-changer, preferably operated by the weight of the receiving-telephone of the annunciator, and which I shall denominate the "battery-switch" to distinguish it from others hereinafter mentioned. When a room occupant desires to call the operator or clerk at the annunciator he closes the branch circuit passing through the said room by any form of key, (herein shown as a key in the telephone itself,) thus causing the annunciator-drop to fall and the signal-bell to sound, and if the said bell is a vibrator, as shown, his telephone will give out a humming sound, owing to the repeated breaking of the circuit, and this sound will inform him that his signal is received. Upon receiving the said signal

the operator at the annunciator removes his receiving-telephone from its hook, and in so doing operates the before-mentioned battery-switch, which then breaks the circuit before described passing from the battery through the bell and annunciator magnets, and at the same time closes a circuit from the battery through the electrodes and primary coil of the battery-transmitter in the annunciator-case. This operation stops the humming sound before mentioned in the signaler's telephone, and the operator at the annunciator at the same time moves a switch, which may be denominated the "room-connecting switch," to a number corresponding to the number of the room signaled from, and thus closes a circuit through the secondary coil of the transmitter and through the telephones at the annunciator and the one in the said room, the said circuit being mainly the same as that before used for signaling, except that the portion then containing the battery and annunciator and signal-magnets is cut out, a shunt passing through the room-switch, annunciator-telephones, and secondary coil of the transmitter taking its place. I shall hereinafter denominate the circuit when passing through the branch containing the signaling instruments the "signaling-circuit," and when passing through the other branch the "talking" or "telephone" circuit. While the apparatus is in the condition last described, with the telephone-circuit closed through one of the rooms, both the talking and signaling circuits from the other rooms are open, the former at the room-switch and the latter at the battery-switch, so that upon closing the key in any of the said rooms no sound will be heard, and it will be understood that the clerk or attendant is communicating with some other person. I have also added a hand-switch in the part of the talking-circuit common to all the rooms to cut out the secondary coil of the transmitter, so that if it is not in working order the magneto-telephones alone can be used, and it is obvious that the battery-transmitter might be dispensed with altogether.

If desired, certain modifications in the circuits may be made, as, when the number of rooms is small, the room-switch and battery-

transmitter might be dispensed with, suitable switches being used to cut out the battery and vibrating bell and close a common talking-circuit to all the rooms which may pass through 5 the annunciator - drops, and a magneto - telephone in the annunciator - case used both for receiving and transmitting.

Figure 1 is a front view of an annunciator embodying my invention. Fig. 2 shows the 10 block for insulating the signaling-keys in the rooms; Figs. 3 and 4, front and side elevations of the annunciator-drop and operating mechanism detached, and Fig. 5 a diagram showing the electric circuit and switches and the 15 position of the instruments therein.

The annunciator *a*, provided with drops *b*, bearing numbers corresponding to the different rooms and adapted to fall behind the openings or windows *c* to announce from which 20 room the signal is received, may be of any usual construction.

A battery-transmitter, *e*, is shown in the annunciator-case, which is also provided with two magneto - telephones, *ff'*, similar in general structure to the ones *d* in the rooms, one of 25 which is hung upon a hook, *g*, to operate the battery-switch *h*. (See Fig. 5.)

It is obvious that one of the magneto-telephones, as *f'*, may be dispensed with; or a single magneto-telephone may be employed in the annunciator-frame in the place occupied by the transmitter *e* instead of the transmitter *e* and telephones *ff'*.

Upon the annunciator-frame is also placed 35 the room-switch, shown as an arm, *i*, capable of being rotated on a bearing around the mouth-piece of the transmitter *e* to bring it in contact with any desired one of the studs opposite the figures 2 3 4 5, &c., which are connected 40 with wires forming a part of the talking-circuits and joining the series passing from the different rooms to the annunciator, the arm *i* being connected with a wire passing through the telephones *ff'* and secondary coil of the 45 transmitter *e* to one of the contact-points of the switch *h*, by which it is connected to the common wire passing to all the other rooms when the telephone *f* is removed from the hook *g*. When there are more studs than can be 50 placed conveniently in one circle around the transmitter they may be placed on several concentric circles, a second one of which is indicated by the studs 7, and the handle *j* of the switch-arm *i* may slide along the said arm, to 55 be brought in position to engage the studs of any of the said circles that may be desired.

Referring to Fig. 5, the circuits and operation are as follows: The parts are shown in their normal position, the telephones *ff'* hung 60 up, and the switch *h*, which consists of two separate movable circuit-closers, *m n*, each provided with two contact-points, one below and one above, in position to close the circuit with the lower contact-points of the two circuit-closers, thus closing the signaling-circuit and leaving the talking-circuit open. Starting 65 from one pole of the battery *k*, the circuit,

which is now in condition for signaling, passes by wire 8 to the contact-point *l* of the arm *m* of the switch *h*. Wire 15 leads off from wire 8, and 70 is a part of the primary of the induction-coil *e'*, and thence by wire 16 comes to the upper contact-point of the arm *n* of the switch *h*, open in the present position of said switch. From the point *l* the circuit passes by the arm *m* to wire 75 9, leading to and connecting all the rooms provided with the signaling apparatus, and having branch wires 10 leading to open keys or circuit-closers in each of the said rooms, (herein shown as the keys *o* in the telephones *d*.) 80 From each of the said open keys are wires 11, each adapted to be connected by the corresponding key *o* with the corresponding wire 10, and each leading through the coils of an annunciator-drop magnet, *p*, to a common wire, 85 12, passing through the magnet *r* of the vibrating signal-bell to the armature thereof, the back stop of said armature being connected with wire 13, passing to the stop *t* of the arm *n* of the switch *h*, whence the circuit is completed by wire 14 to the battery *k*. Branch 90 wires lead from the wires 11 between the telephones *d* and drop-magnets *p*; but these branches are either open at the studs of the room-switch, or, if the arm *i* thereof is connected with any one of said studs, the circuit from the said arm finally comes by arm *i*, wires 23 and 22, arm *w* of switch *w*, wire 21, the secondary coil of *e'*, wire 20, switch-arm *w'*, and wires 19 and 18 to the upper contact-point of the arm *m*, now open. 100

When the occupant of any room desires to signal the office he presses the key *o* at the telephone, which closes the circuit between the wires 10 and 11 corresponding to and leading from the said room, the said key being fully shown in Fig. 2, the metal parts thereof being secured to a block, *o'*, of insulating material, and consisting of an anvil, *o*², connected with the wire 10, and a spring, *o*³, normally out of contact with the said anvil and connected with the wire 11, which passes through the induction-coil *d'* of the telephone. Supposing the room to be the one containing the telephone at A, the operator, pressing the 110 button *o*, brings the spring *o*³ into contact with its anvil *o*², and closes the signaling-circuit just described from the battery *k*, through wires 8 9 10 11 12 to the signal-bell *s*, and thence by wires 13 14 to the battery, the said circuit passing through the coils *p* of the annunciator, drop magnet in the said wire 11 leading from the room in question, to thus operate the said drop, and indicate the room signaled from, and also through the coils of the magnet of the bell 115 *s* and of the telephone *d* at A, thus ringing a signal on the bell *s*, and in so doing causing a vibration of the diaphragm of the telephone *d*, owing to the repeated breaking and closing of the circuit, the said vibration giving out a 120 loud humming sound, which announces to the operator there that his signal is properly operating at the annunciator. The branch circuits 10 11 at the other rooms being all open at the

telephone-keys *o*, no effect is produced in their telephones or annunciator-magnets *p*. When the signal is thus received at the annunciator the operator there raises his telephone *f* from 5 the hook *g* and places the room-switch *i* *j* in contact with the stud connected with the wire leading to the room signaled from—in this instance the one marked 1. When the weight of the telephone *f* is removed from 10 the hook *g* the arms *m* *n* spring up into contact with the points *u* *v*, opening the signal-circuit at the points *t* *l*, and thus stopping the ringing of the bell and sound in the telephone *d*, and at the same time placing the circuit in the proper condition for talking. The 15 battery-circuit is now from the wire 8 by the branch wire 15 through the primary wire of the transmitter induction-coil *e'*, and thence by wire 16 to one electrode of the said transmitter *e*, the circuit being completed from the other electrode by wire 17, arm *n*, and wire 14. The talking-circuit is now as follows: Starting 20 from the anvil *o*² of the key *o* of telephone *d* at A, it passes by wires 10 and 9 to the arm *m* of switch *h*, and thence by wire 18 through the coil of the telephone *f* and by wire 19 to the arm *w'* of the hand-switch *w*, (see figure 1, at the bottom of the annunciator-case,) and then by wire 20 through the secondary coil of the transmitter *e* to wire 21, now connected with the arm *w'* of switch *w*, whence the wire 22 passes to and through the coils of the other telephone, *f'*, at the annunciator, which the operator may use in conjunction with the one *f*, removed 25 from the hook *g* or not, as most convenient, and from which the circuit is completed by wire 23, room-switch *i*, and wires 24 11, through the coil of telephone *d* and spring-key *o*³, to the starting-point *o*². 30

If desired, a single wire, 30, may lead from the wire 12 to a stud, 31, and the room-switch *i* remain in connection therewith, thus completing the talking-circuit to any desired one of the rooms in which the circuit is closed, at 35 the key *o*, the talking-circuit then passing through the coil of the annunciator-drop magnet, unless a drop-switch is used, as hereinafter described.

By the stopping of the humming sound in 40 the telephone *d* the operator at A is informed that the one at the annunciator has taken his telephone *f* and is ready to hear him, and the communication may go on in the usual manner, he holding the key *o* all the time depressed. 45 As before mentioned, the signaling-circuit is now open at the points *t* *l*, so that if a second room occupant closes the key *o* of his telephone no signal will be given and he will have no sound, and will consequently wait and try 50 again.

The hand-switch *w* is to cut out the secondary coil of battery-transmitter *e* from the talking-circuit in case anything is out of order in the said transmitter. By swinging both the 55 arms *w'* *w*² to the left by their connecting insulating-handle *w*³ the arm *w'* is brought into connection with the wire 25^x, thereby making

a direct circuit between wires 19 and 22, and leaving the branch through the wires 20 21 and secondary coil open between 21 and *w*². 70 The communication will then be made by the magneto-telephones *f* *f'*. The switch *w* is shown in Fig. 5 in inverted position.

The annunciator-drops *b*, Figs. 3 and 4, are supported on rods *b'* on a shaft, *b*², pivoted at 75 25 in the frame *b*³ *b*⁴, supporting the magnet *p*, having pole-pieces *p'* *p*² extended upward at the ends of its core.

On the shaft *b*², supporting the drop *b*, is an armature, *b*⁵, extended not quite directly opposite the drop-arm *b'* from the shaft *b*², the said arm being in its normal position, as in full lines, Fig. 7, nearly vertical, and the armature-arms being more inclined and resting against a projection, 26, from the frame *b*³. 80 The result of this arrangement is that the magnet *p'* tends to draw the armature *b*⁵ downward to bring it vertically beneath the shaft *b*², and in coming to this position the shaft *b*² is rocked and the drop *b* carried over the position vertically above the said shaft so far that its weight and momentum now overcome the attraction of the magnet, and the drop passes to the position shown in dotted lines to show from behind a window or opening, *c*, of 90 the annunciator, it being stopped by the projection 27 from the frame *b*⁴.

If desired, the drop may operate a switch to close the talking and open the signaling circuits, as shown at B, Fig. 5, the wire 11 passing to the shaft 25, connected by an arm, 37, with the spring-point 36 and magnet *p*. When the drop falls the said arm 37 breaks the circuit through magnet *p* and closes the circuit through point 38 to wire 24. It is evident that in this 95 arrangement the wires 24 must be in permanent electrical connection with wire 23, the said switch thus performing for its especial branch circuit what the switch *i* does for the collective circuit. The drop *b* is restored to its normal position by one of the knobs or handles *a*², which, when pressed by the operator, acts on an arm, *a*³, from a rock-shaft, *a*⁴, provided with a series of levers, *a*⁵, corresponding to the vertical rows of drops any one of which it is 100 desired to restore. The said levers act on rods *a*⁶, provided with tappets *a*⁷, as many in number as there are horizontal rows of annunciator-drops, each tappet adapted to engage an arm, *b*⁶, on the shaft *b*² and rock the said shaft 105 back to its normal position. After the operator has pressed the knob *a*² to raise a drop, as shown in full lines, Figs. 6 and 7, the knob *a*³ is returned to its normal position by the spring *a*⁸ and the rods *a*⁶ elevated by springs *a*⁹, as 110 shown by the dotted lines, Fig. 4, to again leave the drops *b* free to fall.

The mechanism for returning the drops is made in sections, each to operate a portion of all the drops, such division insuring a better 115 operation and facilitating repair in case the apparatus gets out of order.

As a modification of the arrangement of the circuits shown in Fig. 5, all the apparatus be-

low the broken line x x might be omitted, and that shown in dotted lines take its place, the wire 8 being joined directly to wire 9, as shown at 8^* , and a switch, 50, completing the signaling-circuit to wire 14^* and the battery k . For talking, the switch 50 would be brought into connection with the wire 12, breaking the circuit between wires 13 and 14^* , the current now passing from wire 12 and the said switch by wire 51 through the magneto-telephone f^2 , which might take the place of either of the telephones f^f' , or the transmitter e . The resistance of the battery and annunciator magnet would now be in the circuit, but would not interfere with the communication.

I do not herein broadly claim a key or circuit-closer in a telephone to be held in the hand.

I claim—

1. In combination with a series of transmitting-telephones, circuit-closers, annunciator-drops, signaling and talking circuits, and a central telephone, a rotary switch having a movable piece on its arm adapted to be brought into contact with electrodes located at different distances from the center of rotation, substantially as and for the purposes set forth.

2. In an electric apparatus, the herein-described electric switch, consisting of an arm pivoted to be swung around in a circle and provided with a contact-piece adapted to be moved toward or from the pivoted point of the said arm, and a series of electric circuits terminating in points arranged around the pivotal center of the said arm, whereby a circuit-wire in constant connection with the said arm may be electrically connected with any desired one of the said series of circuits by bringing the said contact-piece in contact with the terminal point thereof, substantially as described.

3. In combination with a series of telephones, a vibrating or circuit-breaking signal and a central telephone, a double switch having its ends insulated from each other, and four electrodes, substantially as and for the purposes set forth.

4. In combination, the four electrodes l t u v and the double switch n m , the latter being united by the insulating-blocks, substantially as and for the purpose specified.

5. The primary circuit having a battery and a battery-transmitter in it, in combination with the secondary circuit having magneto-telephones and a double switch in it, by which switch the secondary coil can be wholly cut out of the magneto-telephone circuit, substantially as described.

6. In combination, a series of telephones each adapted to act both as a receiver and a transmitter, a series of circuit-closers, a series of annunciator-drops, a battery, an induction-coil, and a battery-transmitter, all the telephones adapted to act both as receivers and transmitters being in the secondary circuit of the induction-coil, the battery and battery-transmitter being in the primary circuit of that coil, and these two circuits being controlled by a double switch, so that when one of the series of closers is used to signal, the signal-circuit shall be made up in part of a portion of the wire which, when the transmitter is used, constitutes a portion of the primary circuit of the induction-coil, and when used as a talking-circuit that part of the wire which is in the signaling portion of the circuit shall be cut out, all substantially as described.

7. In an electrical annunciator system, the combination, with the annunciator-drops, of an arm operated by the fall of the drop so as to break the circuit through the magnet of the drop and close the talking-circuit of its special branch, substantially as described.

8. In an electric annunciator and communicating apparatus, the combination, with a branch circuit passing through a room and signaling and communicating apparatus, of a switch operated by the annunciator-drop to connect the said room in circuit with the communicating apparatus and disconnect it from the signaling apparatus, substantially as described.

In testimony whereof I have signed my name to this specification in the presence of two subscribing witnesses.

WILLIAM HUMANS.
